JAMES VAUGHN AND JOHN McGEE, OF GALENA, ILLINOIS.

Letters Patent No. 74,638, dated February 18, 1868.

IMPROVEMENT IN PUMPS.

The Schedule referred to in these Letters Patent and making part of the same.

TO ALL WHOM IT MAY CONCERN:

Be it known that we, JAMES VAUGHN and JOHN McGEE, of Galena, in the county of Jo Daviess, and State of Illinois, have invented new and useful Improvements in Double-Acting Pumps; and we do hereby declare that the following is a full, clear, and exact description thereof, which will enable those skilled in the art to make and use the same, reference being had to the accompanying drawings, forming part of this specification.

The present invention consists in a novel construction and arrangement of the various parts composing the pump, whereby great effectiveness and many advantages are secured, as will be obvious from the following detail description, reference being had to the accompanying plate of drawings, in which—

Figure 1 is an outside view of the pump.

Figure 2, a transverse section in the plane of the line $x x$, fig. 1.

Figure 3, a section taken in the plane of the line $y y$, fig. 1.

Similar letters of reference indicate corresponding parts.

A A, in the drawings, represent the two cylinders of the pump, both of which are hung by trunnion-pins B, the one to one end of a beam, C, and the other to the opposite end of the same, in each case it being suspended between two arms D thereof. This beam C is hung at its centre, so as to have a rocking motion, as through any suitable arrangement or connection of parts it is operated. In each cylinder A, at or about half way between the two ends, which are left open, valves E are fixed for operation. To each cylinder two pistons F are provided, one for each section. G, the rods to pistons F, which rods are made hollow, and at one end are open, while at the other end, or that end having the head, they are provided with valves H. These pistons by their rods are to be fixed or stationary, so that the cylinders will move over or up and down upon them, and thus draw and suck the water up alternately through one piston-rod, while through another of the opposite cylinders it is discharging, and so on as the pump is worked.

We claim as new, and desire to secure by Letters Patent—

The arrangement of the movable cylinders A, pivoted at B in the yokes D at each end of the horizontal rocking-beam C, and fitting over the pistons G, immovably fixed in the framing at each end of the cylinders, all constructed as described, whereby the cylinders are operated by the rocking-beam C, and kept in vertical line upon said pistons by the pins B in the yoke D, as herein set forth for the purpose specified.

JAMES VAUGHN,
JOHN McGEE.
